UNITED STATES PATENT OFFICE.

ROBERT M. SELLECK, OF NEWARK, NEW JERSEY.

GIG-SADDLE TREE.

SPECIFICATION forming part of Letters Patent No. 240,775, dated April 26, 1881.

Application filed October 17, 1879.

To all whom it may concern:

Be it known that I, ROBERT M. SELLECK, of Newark, in the county of Essex, State of New Jersey, have invented a new and useful improvement in Gig-Saddle Trees for Harness, which improvement is fully described in the following specification.

The particular object of my invention is to obtain a saddle-tree for changing mountings after the saddle is made. I present a new kind or style of movable seat for coupé-harness sunken or depressed, where and in which the back-bands travel, as in the old wood tree.

Another part of my invention consists in making a cavity or box in the terret-bar that crosses over the back-band groove on each side of the tree to receive the nuts for the terrets. The large-sized trees differ necessarily from the smaller ones.

In the accompanying drawings, Figure 1 is a top view of a six-inch frame, A, showing the bridges B, the square hole C in the bridges B, to receive the burrs for the terrets, and pad-screws to hold them in place after the saddle is made; the strips a, which help form the bearings and guide the back-bands; the pad-screw holes E; the screw-holes F, for fastening the French coupé terret-bars; the holes f f, for nailing purposes; the holes G, for tuft-nails; the hole H, for the screw which fastens the seat to the frame; the hole I, for the check-hook bolt; the dotted seat j; the channels K, for conveying the pad-screw nuts; the crupper-loop L, and the openings and holes g g, for lightening the frame.

Fig. 2 is a longitudinal sectional view of the frame A, taken on the line z z, Fig. 1, showing the square holes C in the bridge; channels K, to receive the pad-screw nuts; holes E, for the lower pad-screws, and strips a.

Fig. 3 is a central transverse section, showing half of the under side of the frame in elevation, and showing the outlines of the seat j, with the sunken part for the back-bands to pass over outside of the saddle when made up.

Fig. 4 is a view of the French terret-bars as they are secured to the frame by the screws b b over the bridges B, and the box c for the terret-burrs.

Fig. 5 is a view of a cross-section through

the screw-holes, taken on a line, o o, Fig. 2, showing the channel for the lower pad-screws.

Fig. 6 is an outline view of part of a finished saddle, showing the arrangement of the different covered parts, and also showing the coupé-saddle, with sunken seat j', for the back-bands to pass over, the French terret-bar N, and the terret-box c c.

Fig. 7 is a view of the leather pieces Q, with the burrs attached, for guiding them to the hole E in the frame A, to receive the pad-screws s.

Fig. 8 is an outline section of a part of a finished saddle, showing the manner of putting in the pad-screw burrs by means of the leather pieces Q.

Fig. 9 is a view of a coupé-seat, showing the sunken portion h h, where the back-bands pass over the saddle.

Fig. 10 is a view of the terret-base x', with lugs y'.

Fig. 11 is a view of the French coupé terret-bars N, cut crosswise through the center, showing the terret v secured in place, with the burr i i in the box c c, designed to prevent injury to the flaps, and so constructed that any terret can be used without having to make threads in the bars.

Similar letters of reference indicate corresponding parts in all the figures.

In the accompanying drawings, A designates the frame; B, the bridge; C, the square hole in the bridge B, for receiving the terret-burrs, and the burrs for the pad-screws. E designates the pad-screw holes; F, the holes to receive the screws which secure the French terret-bars; G, the tuft-nail holes; H, the hole to receive the screw for fastening on the seat; I, the hole to receive the bolt which holds check-hook; j, the seat, with the sunken portion for the back-bands; K, the channels to convey the pad-screw nuts to their places; L, the crupper-loop; N, the terret-bars; P, the saddle-flaps; Q, the leather pieces to which the pad-screw nuts are fastened; a, iron strips riveted under the bridge for the back-bands to ride on; g g, holes to lighten the frame; f f, holes for nailing purposes; h h, the sunken portion of the bridge j, and b b the screws for securing the French terret-bars.

The box *c c* (shown in Fig. 11) in the terret-bar, for making French coupé-saddles, is to receive the nut *i i*, so as not to interfere with the back-bands.

5 The holes *F* (shown in Fig. 3) are for screws, to hold secure the French coupé-bars, which hold the terrets.

What I claim as my invention, and desire to secure by Letters Patent, is—

10 1. A saddle-tree adapted for changing trimmings, having elevated bridges *B*, and square holes *C* in said bridges to receive the burrs for the terrets, substantially as specified.

2. A harness saddle or tree having longitudinal depression, in combination with a seat having a corresponding depression fitting with the depression in the tree, whereby the back-

band is flush with the upper surface of the tree and seat, substantially as shown.

3. The improved terret-bars described, provided with a box or cavity, *c c*, to receive the terret-burrs, substantially as specified.

4. The combination of the terret-bars, the cavity *c c*, the tree, the terret, and its burr, substantially as shown.

5. The combination, with the open bridge *B*, to admit of the passage and reception of the terret-nut, of the strip *a*, extending across such bridge below, substantially as and for the purpose described.

ROBERT M. SELLECK.
